UNITED STATES PATENT OFFICE.

STANISLAW DAMBROWSKI, OF CENTRAL FALLS, RHODE ISLAND.

RAIL-TIE.

1,295,859.

Specification of Letters Patent.

Patented Mar. 4, 1919.

Application filed September 28, 1918. Serial No. 256,111.

To all whom it may concern:

Be it known that I, STANISLAW DAMBROWSKI, a subject of the Emperor of Austria, residing at Central Falls, in the county of Providence and State of Rhode Island, have invented certain new and useful Improvements in Rail-Ties, of which the following is a specification.

The primary object of the invention is the provision of a railway tie adapted to be anchored to the road bed at either a straight or curved portion of the track whereby added strength and rigidity is given to the railway line resulting in great strength and durability under traffic conditions.

A further object of the invention is the provision of a metallic tie adapted for detachably mounting railway rails thereon, adjustable anchoring means being provided for the tie for bracing the same against the strains of travel as well as securing the tie to the road bed.

A still further object of the invention is the provision of a metallic tie of simple construction which is easy and inexpensive to manufacture, but at the same time possesses great strength and is adapted for locking rails thereon as well as anchoring to the road bed of the railroad line.

With these general objects in view, the device consists of the novel combination and arrangement of parts fully described herein as well as illustrated in the accompanying drawing in which like reference characters designate corresponding parts throughout the several views.

In the drawing,

Figure 1 is a side elevation of the invention with railway rails operatively mounted thereon, parts being shown in vertical longitudinal section;

Fig. 2 is a horizontal sectional view taken upon line II—II of Fig. 1;

Fig. 3 is a side elevation thereof with the anchoring means in a different position and parts broken away; and

Fig. 4 is a vertical transverse sectional view thereof taken upon line IV—IV of Fig. 1.

Referring more in detail to the drawing, my invention provides a hollow tie 10 of substantially inverted trough-shape adapted for positioning upon a road bed, such as 11, for operatively supporting railway rails 12

transversely positioned thereon at the proper 55 gage distance of the railroad.

The top or platform 13 of the tie 10 is provided with opposite marginal flanges 14 adjacent the opposite ends of the tie adapted for the reception of supporting plates 15 60 slidably therebetween. Each of the plates 15 has a foot member 16 positioned through a slot 17 in the platform 13, while an upwardly projecting flange or finger 18 upon the plate 15 is adapted to overlie the outer 65 base flange of the adjacent rail 12. It will be understood that the plates 15 are of greater thickness than the height of the guide flanges 14 so that the entire weight of the rails is supported by the plates 15 without engaging the flanges 14. A separate finger 19 is provided for overlying the inner flange of each of the rails 12, while two bolts 20 extend through the platform 13, plate 15 and finger 19 for retaining the plate and finger 70 engaged with the rail 12 as well as preventing longitudinal movement of the plate upon the tie tending to separate the plate therefrom.

Adjustable anchoring means are detachably positioned within the chamber or hollow interior 21 of the tie 10 in the nature of slabs 22 adapted to project from the tie 10 into the road bed 11.

The slabs 22 are pentagonal in form adapted for sliding within the chamber 21 within opposite ways or grooves 23 formed adjacent the opposite ends of the tie 10 by means of ribs 24 upon the inner faces of the opposite sides of the tie. Opposite sides 25 of the 85 slabs 22 are convergingly arranged for fitting the inclination of the sides of the tie, while a slot 26 is provided in the top of the slab to accommodate the adjacent finger 16. The lower edges 27 of the slabs 22 are sharpened as well as being convergent to assist in pressing the slabs into the road bed 11 for anchoring the tie thereto. The slabs 22 may be mounted in this manner in any other ways 23, such for instance, as projecting in 90 opposite directions after the inclination of the ends 28 of the tie 10 as illustrated in Figs. 1 and 2 of the drawing.

Such a positioning of the slabs 22 is serviceable for a straight line of track but upon 105 a curve where the tie is usually positioned upon a sloping portion of the road bed 11, the slabs 22 may be positioned in relatively

different ones of said ways 23 with one of the slabs substantially vertical and the other outwardly inclined as illustrated in Fig. 3. The slabs 22 may be withdrawn from the road bed when required, although affording ample anchoring facilities when in use, it being obvious that any set of ways 23 are employed which are found to be the most serviceable. A tie is provided which possesses great strength and durability readily anchored upon the road bed at any desired position for use in supporting railway rails.

What I claim as new is:

1. A tie comprising an inverted trough shaped member having a rail supporting top, spaced ribs oppositely provided in pairs within the same adjacent the opposite ends of the device forming ways, and pentagonal slabs removably positioned within said ways

having lower sharpened edges projecting from the tie adapted for engaging the road bed.

2. A device of the class described comprising a hollow tie having ways within its interior adjacent its opposite ends, anchoring slabs removably positioned within said ways having a projecting portion provided with sharpened edges.

3. A device of the class described comprising an inverted trough-shaped tie, opposite pairs of guide ribs provided within the tie, anchoring slabs removably positioned within the tie, anchoring slabs removably positioned within the tie adjacent said ribs and having pointed portions projecting beneath the tie adapted for engaging the road bed.

In testimony whereof I affix my signature.

STANISLAW DAMBROWSKI,

Copies of this patent may be obtained for five cents each, by addressing the "Commissioner of Patents,
